UNITED STATES PATENT OFFICE

2,651,432

SEALED SHIPPING CONTAINER

Ralph S. McConnell, Silver Spring, Md.

Application February 16, 1950, Serial No. 144,450

1 Claim. (Cl. 217—89)

1

This invention relates to shipping containers and an improved sealing means for sealing the container against pilferage.

An object of this invention is to provide an improved shipping container embodying a collapsible side wall formed of banded staves, and opposite end heads with an improved means for holding the heads in position, each head being formed of a disc-shaped member with an angle-shaped ring secured to the outer side thereof, and the ring being secured to the side wall by means of removable pins.

Another object of this invention is to provide a shipping container of this kind with an improved means for sealing the securing pins so that unauthorized opening of the container can be readily detected.

A further object of this invention is to provide in a collapsible shipping container having a separable side wall, an improved sealing means for locking and sealing the connectors together.

In one form of the invention a plurality of U-shaped clips engage over the ends of the side wall of the container and over the angle-shaped rim on the head and headed pins extend through the parallel legs of the clips with a sealed together wire threaded through the inner ends of the pins. A pair of the clips engage over the outer ends of the outer connectors with a common pintle engaging through the aligned connector barrels so that the pintle is held against endwise movement.

In a modified form of this invention the ends of the common pintle for each series of aligned connector barrels are threaded into short straps or plates which extend inwardly over the ends of the sides, and the plates are held against unthreading from the pintles by means of a wire engaging through pins which are extended through the plates.

In another form of this invention separate headed pintles are used for the connectors and each pintle is locked by means of a wire seal.

With the above and other objects in view, my invention consists in the arrangement, combination and details of construction disclosed in the drawings and specification, and then more particularly pointed out in the appended claim.

In the drawings:

Figure 1 is a perspective view of a collapsible container constructed according to an embodiment of this invention.

Figure 2 is a fragmentary plan view of the container.

Figure 3 is a sectional view partly broken away taken on the line 3—3 of Figure 2.

2

Figure 4 is a fragmentary sectional view taken on the line 4—4 of Figure 2.

Figure 5 is a fragmentary sectional view taken on the line 5—5 of Figure 3.

Figure 6 is a fragmentary sectional view taken on the line 6—6 of Figure 2.

Figure 7 is a fragmentary sectional view showing a modified form of this invention.

Figure 8 is a fragmentary sectional view showing another modification of this invention.

Figure 9 is a fragmentary sectional view showing the sealing means for the end locking wires.

Figure 10 is a fragmentary sectional view of another modified form of this invention.

Figure 11 is a fragmentary sectional view showing another modification of this invention.

Referring to the drawings the numerals 10 and 11 designate generally a pair of semi-cylindrical side wall members which are formed of staves 12 which are secured together by means of metal bands 13 and 14. The side wall members 10 and 11 are coupled together by means of coupling members 15 and 16 formed with complementary barrels 17 and 18, respectively. The barrel 17 includes a relatively long shank 19 forming a space 20, the purpose for which will be hereinafter described.

A pair of end heads 21 and 22 of disc shape are adapted to engage in the opposite ends of the container formed by the connected side walls 10 and 11, and each head 21 has secured by fastening means 23 to the outer side thereof an angle-shaped ring or rim 24. One side of the rim 24 is disposed in face abutting relation to the head 21, and the other side 25 of the rim 24 is disposed in face abutting relation to the projecting ends of the staves 12. The outer edge of the side 25 is adapted to be disposed flush with the adjacent ends of the staves 12.

A cleat 26 is secured by fastening means 27 to the inner side of each stave 12 and forms a stop means or abutment against which the inner side of the head 21 is adapted to engage.

An elongated rod 28 extends through the aligned connector barrels 17 and 18 of each series of connectors, and a U-shaped clip or locking member generally designated as 29 engages over the outermost connector and also over the outer ends of the side wall members 10 and 11. Each clip or locking member 29 includes a bight member 30 which extends across the end of a side wall and overlies the adjacent end of an outermost connector and the adjacent end of the common pintle 28. The outer side or leg 31 of the clip 29 engages over the outer side of the barrels

17 and 18 as shown in Figure 3; whereas, the inner side 32 of the clip 29 projects inwardly in overlapping relation with respect to the outer side 25 of the rim 24. A locking pin 33 is extended through the clip sides 31 and 32 and projects through the space 20 of the adjacent connector and also through the adjacent stave 12 and the outer side 25 of the rim 24.

The inner end portion of the locking pin 32 is formed with an opening 34 through which 10 a sealing wire 35 is threaded. There are a series of these U-shaped clips 29 disposed in circumferentially spaced apart relation about the container, and as shown in Figure 6 the intermediate clips 29a are slightly shorter than the clips 29 and engage against the outer sides of the staves 12. After the locking wire 35 is threaded through the pin openings or keepers 34, the ends of the wire 35 are brought together in either overlapping or twisted relation and are 20 securely fixed together by a sealing member 36 in the form of lead or the like.

Referring now to Figure 7 there is disclosed a modified form of this invention wherein the connector barrels 17a and 18a for the aligned series 25 of connectors have a common pintle or locking member 28a extended therethrough. The opposite ends of the pintle 28 project beyond the outermost connectors as shown in Figure 7, and a locking plate or strap 37 is threaded onto each 30 end of the pintle 28a and projects radially inwardly across the end of the adjacent stave 12.

A headed pin 38 is extended through an opening 39 formed in the inner portion of the plate or strap 37 and is formed with an opening 40 through which a locking wire 41 similar to the wire 35 is adapted to be threaded. The ends of the wire 41 are adapted to be sealed together by a seal means similar to 36 as shown in Figure 9. It will be understood that the U-shaped clips 29a 40 will be used at the intermediate points between the diametrically opposed plates 27 at each end of the container.

Referring now to Figure 8 there is disclosed another modification of this invention where the barrels 17b and 18b have separate headed pintles 42 extended therethrough and a locking wire 43 is threaded through an opening 44 formed in the pintle 42 for locking the pintle against endwise movement, and the ends of the wire 43 are sealed together by means of a lead seal 45. The angled rim 24b which is secured to the head 21b is detachably secured in the adjacent end of the container by means of headed pins 33b which have locking wires 46 threaded through holes 47 in the inner portions of the pins 33b, and the ends of the wire 46 are sealed by means of a lead seal 48. It will be understood that if desired the U-shaped clips 29a may be used at spaced points between the connectors shown in Figure 8.

The provision of the angle shaped rim on the outer face of each head for the container provides a means whereby the projecting ends of the staves will be reinforced so that the projecting ends of the staves will not be broken or cracked when the container is rolled on an edge of each end.

The container and sealing means therefore hereinbefore described will provide a pilfer proof container which cannot be opened by an unauthorized person without the opening of the container being readily detected. In one use for this container it is contemplated that crockery, china, or other similar articles be placed within the container for import or export. It has been found that containers at present in use for articles of

5 this kind are very frequently broken into and the articles removed, and the containers again closed without the unauthorized opening being readily detected. However, with a container as hereinbefore described, the unauthorized opening of the container can be readily detected so that the shipper will be amply protected against unauthorized removal of the articles from the container.

Referring now to Figure 10, there is disclosed another modification of this invention wherein a U-shaped clip 29c is used at spaced points about the ends of the side walls and a headed pin 33c extends through the parallel sides of the clip 29c and through the outer side 25c of the angle shaped rim 24c. An inwardly projecting apertured lug 49 is struck from the clip 29c, and a locking wire 50 is extended through the opening in the lug 49 and through an opening 51 formed in the pin 33c.

Referring now to Figure 11 there is disclosed another modification of this invention wherein the side wall structure 10d is formed with openings 52, and a flanged head 21d engages within the end of the side wall 10d. The head 21d is formed of a flat body 53 having a rim 54 secured thereto and forming a flange which is flush at its outer edge with the edge of the body 53. The ring 54 is formed with openings 55 aligning with openings 52 in the side wall and headed holding pins 33d are extended inwardly through the aligned openings 52 and 55. The pins 33d are locked against outward movement and also sealed against unauthorized removal by sealing wires 46d.

What is claimed is:

A shipping container comprising a cylindrical body formed of staves, cleats secured to said staves inwardly of each end thereof, a pair of disc-shaped heads disposed one in each end of said body and bearing against said cleats, an annular rim secured to the outer side of said head, said rim being L-shaped in transverse section with one side disposed in face abutting relation to the outer face of said head, the other side of said rim being flush with the marginal edge of said head and projecting outwardly of said head in confronting position with respect to the adjacent end portions of said body, a plurality of U-shaped clips at each end of said container, said clips engaging over the ends of said staves and overlapping said other side of said rim, each leg of each clip and associated stave and overlapped side of said rim having aligned openings, a headed pin extending through said aligned openings, an apertured lug extending from the bight of said clip and projecting radially inwardly with respect to said head, said pin having an opening, and a sealing wire extending through the opening of said lug and said pin.

RALPH S. McCONNELL.
